[57] CLAIM

The ornamental design for “stretchable and foldable cart”, as shown and described.

DESCRIPTION

FIG. 1 is a perspective view of a stretchable and foldable cart showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof; and,

FIG. 8 is a perspective view of stretchable and foldable cart in a contractive and folded state according to the present design.
